UNITED STATES PATENT OFFICE.

ADA MONTAGUE HEWITT, OF DETROIT, MICHIGAN.

DESIGN FOR A TOY INSECT.

Application filed June 19, 1922. Serial No. 2,730. Term of patent 7 years.

To all whom it may concern:

Be it known that ADA MONTAGUE HEWITT, a citizen of the United States of America, residing at Detroit, in the county of Wayne and State of Michigan, has invented a certain new, original, and ornamental Design for Toy Insect, of which the following is a specification, reference being had therein to the accompanying drawings, forming part thereof, in which Fig. 1 is a side elevation of my invention, Fig. 2 is a front elevation thereof, and Fig. 3 is a top view thereof.

I claim:

The ornamental design for toy insect, substantially as shown.

ADA MONTAGUE HEWITT.
